BRUCE E. SWITZLER, OF SANTA ANA, CALIFORNIA, ASSIGNOR TO W. O. THOMPSON, OF PASADENA, CALIFORNIA

COMBINED MEMORANDUM AND FILING DEVICE

Application filed September 7, 1928. Serial No. 304,537.

This invention relates to a combined calendar, memorandum and filing device, the general object of the invention being to provide a body having means therein for supporting a roll of paper, a pad hingedly connected with the body and over which the paper is adapted to be passed so that notes can be made thereon, a filing device arranged under the pad and uncovered when the pad is raised and a calendar pad supporting device arranged at the upper end of the body.

Another object of the invention is to provide means on the under side of the pad for holding a card which may contain addresses and telephone numbers.

A still further object of the invention is to provide means for facilitating the drawing of the paper over the pad and for tearing off portions of the paper after it has been passed over the pad.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of the device with the pad in raised position.

Figure 2 is a plan view with the pad in lowered position.

Figure 3 is a front view of the device with the pad in raised position.

Figure 4 is a section on line 4—4 of Figure 1.

Figure 5 is a section on line 5—5 of Figure 2.

Figure 6 is a sectional view on line 6—6 of Figure 5.

Figure 7 is a sectional detail view through portion of the calendar pad supporting means, showing one of the uprights which passes through the perforations in the sheets of the pad.

Figure 8 is a perspective view of the pad supporting member.

Figure 9 is a view of the roller which supports the roll of paper.

In these views, 1 indicates the body of the device which has its sides turned up to provide the flanges 2 and then the upper edges of the flanges are turned over to produce the gutters 3 which are adapted to hold pencils, pens and the like. The flanges taper upwardly toward the rear where they merge into the enlargements 2' which form a chamber for the roll of paper, shown at A. A substantially U-shaped cover 4 has its long limb hinged to the rear end of the body by the rod 5, with its short limb terminating a distance from the small flanges 2. The parts 2' have vertically arranged slots 6 therein for receiving the ends of the roll 7 upon which the paper roll A is placed. This roll 7 is provided with the knobs 8 at its ends for facilitating rotation of the paper roll.

A hollow pad member 9 is pivoted in the body by means of the pintles 10 arranged a short distance from the enlarged rear end of the pad member engaging holes in the flanges 2. A pair of rollers 11 have their pintles journaled in the enlarged rear end of the pad member, these rollers being arranged one above the other and are preferably formed of rubber or the like. One of the pintles extends through an arc shaped slot 12 in one of the flanges 2 where it receives a knob 13 by which the rollers can be rotated. A cross piece 14 extends across the rear end of the pad member in rear of the top roller and its lower edge forms a knife 15 for a purpose to be hereinafter described.

A guiding roller 16 is placed in each end of the hollow pad member 9 for guiding the paper strip through said pad member. This paper strip, coming from the roll A, is passed under the bottom roller 11 through the hollow pad member 9, where it is turned over the front roller 16 and brought back over the top of the pad member and through the rollers 11 and under the knife edge 15, with its end projecting upwardly in the space formed by the enlarged end of the pad member and the front of the paper chamber. This will place a portion of the paper on the top of the pad member where it can be written upon and

when a new surface of paper is desired, it is simply necessary to turn the knob 13 with one of the fingers to rotate the rollers 11 which will feed the paper from the roll A through the pad member and over the same. 5 The portion of the paper used can be drawn off by simply pulling it against the knife edge 15.

10 The lower part of the pad member 9 is formed with the holding strips 17 for holding a card 18 on the rear face of the pad member and this card may contain spaces for the names, addresses and telephone numbers, as shown in Figure 1. The ends of the sides of 15 the member 9 are extended at the front, as shown at 19, to form finger pieces for facilitating the raising and lowering of the pad member, it being understood that this pad member enters the space between the flanges 20 when it is in lowered position. Rearwardly and downwardly extending arms 20 are formed on the enlarged end of the pad member and a filing device 21 has a shaft 22 at its rear end which is carried by said arm so that 25 when the pad member is raised, the device will be moved forwardly so that it will project from the front end of the body, as shown in Figures 1 and 4, but when the pad member is lowered, the filing device will be pulled back into the body, as shown in Figures 2 and 5. 30 This device is formed of a series of leaves 23 which are of gradually increasing width, each leaf having an index strip 24 at its front end. The matter to be filed is placed between 35 the leaves in the well known manner.

40 A holder 25 for a calendar pad 26 has a curved front part 27 for engaging the upper front part of the paper roll chamber and it has projections 28 which engage notches 29 in the flanges 2 where they join the enlargements 2' so that the calendar pad is supported above the roll chamber and to the rear thereof. The pad member 9 will rest against the calendar pad when said member is in raised 45 position, as shown in Figure 4. The member 25 has an upwardly extending flange 30 at its rear and it has a pair of uprights 31 for passing through the perforations in the calendar pad. Set screws 32 hold the leaves on the 50 uprights.

55 A curved flange 33 extends outwardly from the lower part of the curved portion 27 and is designed to prevent the paper coming from between the rollers 11 from entering the paper chamber, as this flange causes the paper to pass upwardly through the space between the rear end of the member 9 and the front of the paper chamber.

60 From the foregoing it will be seen that I have provided a neat and compact arrangement for holding a roll of paper and for directing the strip of paper from the roll over a pad member where the paper can be written upon, with means for filing memoran- 65 dums and the like in separate compartments

arranged under the pad member and which are accessible by raising the pad member and also means for holding a calendar pad at the rear end of the device where it is out of the way yet where the data on the sheets of the 70 pad can be readily seen. The gutters also act to hold pencils and pen holders.

75 With this invention, a person can keep his desk clear of calendars, blotters, pads for making memorandums and the like.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a body of channel shape in cross section, a hollow pad member having its ends open pivotally mounted in the body, a chamber formed at the rear of the body for holding a roll of paper, means for guiding the strip of paper from the roll through the pad member and back over the top of the same, rollers at the rear end of the pad member through which the paper passes, means for rotating the rollers manually to feed the paper through the same and a filing device slidably arranged in the body under the pad member and pivotally connected with the rear end of the pad member so that it will be partly projected from the body when the 100 pad member is raised.

2. A memorandum device comprising a hollow body, means for supporting a supply of writing material in a part thereof, a tiltable platen normally covering said memorandum holding means, and means associated with said platen and said holding means for moving said holding means to a readily accessible position when said platen is tilted.

105 3. A device of the character described comprising a receptacle, a movably supported pad member forming a cover for said receptacle and provided with means for guiding a strip of writing material, a filing device slidably arranged within said receptacle, and means connecting said filing device with said pad member, so that sliding movements will be imparted to the filing device by movements of the pad member.

110 4. A device of the character described comprising a receptacle, a pad member pivotally supported at one end by said receptacle and free at its other end so that it may be tilted, said pad member having means for guiding a strip of writing material, a filing device slidably arranged within said receptacle, and means contiguous to said pivotal support for connecting said filing device with said pad member, so that sliding movements will 130

be imparted to the filing device by movements of the pad member.

5. A device of the character mentioned comprising a receptacle, a movably supported pad member forming a cover for said receptacle and provided with means for guiding a strip of writing material, a filing device slidably arranged within said receptacle, arms projecting from said pad member, and
10 a shaft carried by said arms and engaging said filing device, so that sliding movements will be imparted to the filing device by movements of said pad member.

15 6. In a memorandum device, means providing a chamber, a filing device movably mounted within said chamber, a movable platen connected with said filing device so as to impart movements thereto, said platen forming the cover for said chamber.

20 7. A memorandum device of the character mentioned comprising a hollow body, a pad member pivoted at one end between the sides of said body, said pad member having means for guiding a portion of a strip of paper in one direction, one of the sides of said body having an arcuate slot therein, feed rollers carried by said pad member and positioned to guide said strip of paper in the other direction, one of said rollers having an extension projected through said slot, and operating means carried by said extension.

25 8. A memorandum device of the character described comprising a hollow body having means for supporting a roll of paper, a pad member pivotally connected with said hollow body and having means for guiding a strip of paper from said roll, means carried by said pad member for imparting movement to said strip, and a guide member having laterally extended portions removably engaging the sides of said body and having a deflecting flange positioned adjacent to said movement imparting means, so as to deflect said strip of paper outwardly as it is fed.

30 45 In testimony whereof I affix my signature.
BRUCE E. SWITZLER.
